UNITED STATES PATENT OFFICE.

STEPHEN M. WIRTS, OF DETROIT, MICHIGAN, ASSIGNOR TO THE FARRAND COMPANY, OF DETROIT, MICHIGAN, A CORPORATION OF MICHIGAN.

DESIGN FOR A CASING FOR PLAYER-PIANOS.

● 40,504.

Specification for Design.

Patented Feb. 8, 1910.

Application filed October 30, 1909. Serial No. 525,600. Term of patent 7 years.

To all whom it may concern:

Be it known that I, STEPHEN M. WIRTS, a citizen of the United States of America, residing at Detroit, in the county of Wayne and State of Michigan, have invented a certain new, original, and ornamental Design for Casings for Player-Pianos, of which the following is a specification, reference being had therein to the accompanying drawings, forming part thereof.

The figure is a perspective view of a casing for a player piano, showing my new design.

I claim,—

The ornamental design for a casing for a player piano, as shown.

STEPHEN M. WIRTS.
